A. F. ABLE, OF NEW ORLEANS, LOUISIANA, ASSIGNOR TO HIMSELF AND
A. D. FINLEY.

Letters Patent No. 97,850, dated December 14, 1869.

HUMMING-WHEEL TOY.

The Schedule referred to in these Letters Patent and making part of the same.

To all whom it may concern:

Be it known that I, A. F. ABLE, of the city of New Orleans, in the parish of Orleans, and State of Louisiana, have invented a new and improved Humming-Wheel Toy; and I do hereby declare that the following is a full, clear, and exact description thereof, which will enable others skilled in the art to make and use the same, reference being had to the accompanying drawing, forming part of this specification.

This invention relates to improvements in humming-wheel toys, having for its object to provide an improved holding-apparatus for supporting and maintaining the proper tension on the cords, and designed to support the cords of two or more wheels at the same time.

The drawing represents a side elevation of my improved apparatus.

A represents a pair of bent cord-holding rods, pivoted together at B, and suitably shaped below the pivots to form handles; above the pivots they are bent abruptly in opposite directions, and suitably shaped for the support of two or more double cords, C, of ordinary humming-wheels.

For engaging and holding these cords, I propose to provide two or more catches, D, and these I propose to shape, for the purpose of ornament, in the form of birds, the uppermost so arranged as to hook the loop of the cords under the crest, as shown at E, and the lower ones to hook the loop under the beaks, as shown at F.

When the cords are engaged with the said catches,

and twisted a sufficient amount, the pressure of the hands on the handle, together with the rotative force of the twisted cords, will set the wheels into motion, and maintain them so for a long time, as is well understood.

The cords may be twisted up by one hand, while holding the implement in the other hand, or one cord with its wheel may be placed on the top catches, and twisted, by properly swinging the support, to give a circular motion of the wheel around the axis of the cord in a well-known way, and then laying it down to prevent untwisting, until the other can be placed on its catches and twisted up by the hand.

Other methods of setting two or more wheels into motion at the same time may be employed.

Having thus described my invention,

What I claim as new, and desire to secure by Letters Patent, is—

1. The bent arms A, hinged at B, suitably shaped for handles at one end, and shaped at the other, and provided with two or more sets of cord-holding catches, D, all substantially as specified.

2. A toy humming-wheel device, consisting of the bent hinged rods A, two or more sets of catches, D, and two or more humming-wheels and cords, all substantially as specified.

A. F. ABLE.
